UNITED STATES PATENT OFFICE.

HARRY B. PALMER, OF NEW YORK, N. Y., ASSIGNOR, BY MESNE ASSIGNMENTS, TO
GEORGE E. SLY, OF NEW YORK, N. Y.

EMPLOYEE'S TIME-RECORDER.

1,025,879.

Specification of Letters Patent.

Patented May 7, 1912.

Application filed January 6, 1905. Serial No. 239,842.

To all whom it may concern:

Be it known that I, HARRY B. PALMER, a citizen of the United States, and a resident of New York, in the county of New York and State of New York, have invented certain new and useful Improvements in Employees' Time-Recorders, of which the following is a specification.

My invention relates to a machine for making records of a workman's employment wherein is employed a time-controlled imprint-making element and a carrier for an imprint-receiving element, and particularly to means for effecting spacing between the entries, or imprints, made on successive occasions by a workman, and the object of the invention is to provide a machine of this character which is particularly simple in construction and highly efficient in use.

One embodiment of the invention is hereinafter specifically described in connection with the accompanying drawings, wherein—

Figure 1 is a front elevation of a time-recorder exhibiting the invention. Fig. 2 is a similar view, partly in section, and with the casing removed. Fig. 3 is a vertical section of the same on the line 3—3, Fig. 2, looking in the direction indicated by the arrow and showing the parts in their initial positions. Fig. 4 is a similar view showing the parts in the positions assumed thereby at the end of an imprint-making operation. Fig. 5 is a diagrammatic view of the system associated with the imprint-making wheels. Fig. 6 is an enlarged front elevation of a portion of the imprint-making element; and Fig. 7 is a sectional view on the line 7—7, Fig. 6.

The invention includes generally an imprint-making element, a support for a record element designed to receive imprints, or entries, spaced apart and individual to a workman, and means individual to a workman for automatically effecting, or determining, the spacing between the entries, or the positions of the entries in the record space.

The embodiment of my invention, selected for the purpose of illustrating the same, discloses a single sheet 73, containing a plurality of record spaces, each individual to a workman. Imprints, or entries, are made in these spaces by an imprint element comprising time-printing wheels 46, 49. The imprint element is movable in one direction for alining it with a selected workman's rec-

ord space, is normally maintained in a position of rest, or initial position at corresponding ends of such spaces, and is movable from such position of rest, or initial position, lengthwise of the record spaces. 60 The extent of this movement is determined by displaceable parts 75 arranged in sets, or groups, each being individual to one record space, and a single member 23 movable with the imprint element and common to all of 65 the displaceable parts 75 coöperates therewith.

It will be understood that a set of displaceable parts 75 is associated with each record space and each displaceable part of 70 each set is complemental to an independent portion of its record space; the general arrangement being such that each set of displaceable parts determines the spacing of the imprint element for the associated record 75 space and does not affect the spacing of the imprint element for any other record space and, consequently, the spacing of the entries for each workman is effected entirely independently of the spacing of the entries 80 for any other workman.

The illustrated embodiment of my invention further includes a manual, or handle, common to all the workmen, which is adapted to be shifted in one direction into a 85 plurality of positions, each corresponding to one record space, and this movement, through suitable interposed mechanism, alines the selected record space and the imprint element. The manual or handle is also shiftable in a second direction, which, through interposed mechanism, effects a movement 90 of the imprint element lengthwise of the selected record space.

The illustrated machine is so constructed 95 that the second movement of the handle is of a uniform length, or extent, and sufficient for effecting a movement of the imprint element the full length of any record space, but the imprint element is designed to be arrested at variable positions, as determined by the aforesaid displaceable parts 75, short of its full range of movement.

The illustrated machine also includes a device coöperating in one movement with 105 all of the displaced parts 75 for restoring the same to initial positions, such device comprising a plate 78 movable about an axis 80.

With this general outline of the illustrated 110

structure, the same will now be described more in detail.

The main frame of the machine is designated 1 and may be secured to a suitable support by means of screws or the like passing through openings 8. This frame includes a sub-frame 2 for supporting parts to be hereinafter described.

Certain of the parts of the mechanism are intended to be beyond the control of the workman, and are mounted on the frame 1, or sub-frame 2, and are inclosed by a casing 3, pivoted at 4 near one edge, and held to the frame 1 at a point separated from the point 4 by a rod 12 engaging alining openings in lugs 11 projecting from the frame 1, and openings in the sides of the casing. The rod is held against accidental displacement by a suitable pin 13 extending through an opening at one end thereof and is provided at its other end with a knob 14. An opening is provided in the side of the casing for giving access to the interior thereof and this opening is normally closed by a door 9 provided with a knob 10. Brackets 14 extend outwardly from the upper portion of the sub-frame 2, at opposite sides thereof, and support a cylindrical guide rod 15 provided with stop collars 16, retained in position on the rod by set screws 17. Slidably mounted upon the guide rod 15, and adapted to oscillate thereon, is a bearing sleeve 18 provided with vertically disposed bearing barrels, or sleeves, 19.

Mounted within the bearing sleeves 19, and free to slide relatively thereto, are rods 20, the upper ends of which are provided with lock-nuts 21, forming limiting stops for the said rods 20. The rods 20 are rigidly secured to and form parts of a recording frame, the main elements of which are shown at 22, the lower end of said frame being formed by a depending arm 23, provided with a foot 24, as indicated more particularly in Figs. 3 and 4. Spiral springs 25 encircle the rods 20 and engage the upper ends of the bearing sleeves 19 and the lower ends of bearing sleeves 26, so as to exert more or less tension. The bearing sleeves 26 are rigidly connected with an arm 27, to which is fastened by means of a stem 28 a knob 29, this stem 28 being rigidly secured within a head 30 integral with the arm 27, as indicated more particularly in Figs. 3 and 4. The springs 25 tend to force the sleeves 26 against the nuts 21 and act thereby for holding the elements 22 in contact with the sleeves 19, such contact determining the extreme upward position of the frame. When the frame occupies its extreme upward position the imprint element, to be hereinafter described, and which is mounted in and movable with the frame, is held at its extreme upward position, hereinafter referred to as its normal position or

position of rest. The knob 29 and arm 27 are movable in one general direction into a plurality of positions, each individual to a workman, or into alinement with any one of the slots 5, and thus the imprint element, 70 and any desired record space on the receiving element, may be alined. The knob 29 and arm 27 when in any one of the aforesaid positions may be given an additional movement in a direction lengthwise of the 75 alining slot 5 for effecting movement of the imprint element lengthwise of the record space in registration therewith.

A blocking-bar 31 is rigidly secured within the casing and is disposed immediately 80 adjacent to the slots 5 and 6. A bell 32 is mounted upon a lug 33, connected with the bearing sleeves 26. The bell is provided with a clapper 34, and with a spring tripping finger 35. The arrangement of the 85 parts is such that when the knob 29 is depressed to a point where the head 30 is adjacent the under side of the blocking-bar 31, as indicated in Fig. 4, the springs 25 are compressed as shown in that figure, the bell 90 meanwhile passing downward so that the spring finger 35 is tripped by the stop 7, thereby causing the clapper 34 to strike the bell. When, however, the pressure of the hand upon the knob 29 is released so that 95 the tension of the springs 25 carries the bearing sleeves 26 and bell 32 back into the normal position indicated in Fig. 3, the spring finger 35 merely swings downward and slides past the stop 7.

A two-pole magnet is shown at 36 and is provided with an armature 37, this armature having a guide aperture 38 in which loosely works a guide-pin 39. Lock-nuts 40 are mounted upon the outer end of this guide-pin and serve as a limiting stop for the armature. The armature is mounted upon a post 41, being pivoted thereupon at the point 42. A spring 43 normally retains the armature 37 in the position indicated in 100 Fig. 3. A pawl 44 is pivoted upon the armature 37 and engages a ratchet-wheel 45, to which a wheel 46 is rigidly connected. The wheel 46 is provided with a contact-pin 47, which engages a spring-arm 48, forming an 105 electrical contact therewith, as indicated more particularly in Fig. 5. The wheel 46 is provided with raised ordinals indicating subdivisions of time, preferably fractions of an hour. If desired, there may be twelve 110 of these ordinals placed upon the type-wheel 46, indicating that the hour is divided into periods of five minutes each. A somewhat similar wheel 49 is disposed immediately adjacent to the wheel 46, and is also provided with raised ordinals, but of a different denomination from the ordinals upon the type-wheel 46. Upon the type-wheel 49 the ordinals preferably represent hours and are twenty-four in number, so as to repre- 115

- sent the entire day and night. These ordinals are arranged in two groups of twelve each, the groups being distinguished from each other preferably by the style of type.
- 5 The heavy ordinals, for instance, may represent the night time, and the lighter ones the day time.
- The type-wheels 46 and 49 are mounted in bearings 50 and constitute an imprint element. A ratchet-wheel 51 is secured rigidly to the type-wheel 49 for the purpose of causing the rotation thereof. A pawl 52 is pivoted upon an armature 53, this armature being in turn pivoted at 54, and free to move toward and from a magnet 55. This armature, pawl and ratchet are similar to those already described. A wheel 56, driven by clockwork, is provided with contacts 57, which engage a resilient contact-arm 58, thereby forming an electrical contact. The contact-arm 58 is connected by means of a wire 59 with the magnet 36, this magnet being connected by means of a wire 60 with a battery 61. A wire 62 is connected to the wire 60, at one side of the battery, as indicated more particularly in Fig. 5, and is also connected with the spring-arm 48. A wire 64 is connected with the wire 60, at the other side of the battery, and with the magnet 55, this magnet being in turn connected by means of a wire 63 with the axle 49^a of the wheel 49. The number of contacts 57 upon the wheel 56 corresponds with the number 35 of ordinals upon the type-wheel 46, and on engagement of the spring-arm 58 by a contact 57 the type-wheel 46 is turned a distance corresponding to the angular interval between a pair of adjacent contacts 57.
- 40 Each time the wheel 46 makes a complete revolution, the contact formed by the pin 47 and the spring-arm 48 is closed, thereby energizing the magnet 55, as will be readily understood from Fig. 5.
- 45 The successive intermittent movements of the type-wheel 49 cause one complete rotation of the same every twenty-four hours, because each rotation of the type-wheel 46 results in the type-wheel 49 being turned 50 one twenty-fourth of a revolution. With the arrangement described, the type-wheels 46 and 49 together present ordinals at a given point in such manner as to indicate the hours of the day and the five-minute 55 fractions of an hour.
- Any suitable inking means may be employed, but I have shown a spool 65 (see particularly Fig. 7) provided with a retracting spring 66, and partially wound 60 with an ink ribbon 67, which is firmly secured at 68 to the bracket 19, this end of the ribbon being thereby rendered immovable. The descent of the frame 22, as indicated in Fig. 4, causes the spool 65 to partially unwind, thereby unwinding the rib-

bon in the form of a web, having more or less tension, and disposed substantially parallel with the general direction of the frame. When the frame is swung into the position indicated in Fig. 4, the ordinals upon the wheels 46 and 49 are successively pressed against the ribbon 67, and a record thus made on any surface which may be at the opposite side of the ribbon.

The sub-frame 2 is shaped to form a large space 69, shown more particularly in Figs. 3 and 4. Within this space is loosely mounted a plate 70, against which bear pins 71 passing loosely through the back of the sub-frame, these pins being provided with springs 72 for forcing them and the plate forward. The record-receiving element is supported upon the face of the plates 70 and is here shown as a sheet or card having a plurality of record spaces 80 arranged side by side on its face, each designed to be assigned to an individual workman. These cards are placed in position by opening the door 9 and sliding the cards endwise into the space 69 between the plate 70 and the clips 74, which serve to hold the edges of the cards and also to expose enough of the surface thereof to enable the cards to be printed.

A plurality of displaceable parts 75 in the form of pins are slidably mounted in the sub-frame 2. These parts are grouped in independent sets, each set being supplemental to an individual workman or an individual record space on the receiving 100 element, or to one of the aforesaid positions in which the knob 29 and arm 27 are shifted for alining the imprint element with a particular record space, and each part corresponds to an individual imprint-receiving 105 point or position on the imprint-receiving element. The pins are provided with heads 76 on their rear ends which act for limiting the movement thereof in the resetting of the same.

A resetting device, such as a board 78, normally retracted by a spring 79, is pivoted at 80 upon the casing, and may be controlled by means of a finger-piece 81, shown in Fig. 1. By operating this finger-piece 115 the board 78 may be thrown against the heads 76 of the pins, thereby leveling them all up, and restoring them to their normal positions indicated in Fig. 3. This movement may be effected, say every night, or 120 at the close of business hours.

The general operation of my improved time-recorder is as follows: Each of the numbers shown in Fig. 1 represents a particular employee. One of the employees, say 125 number 13, comes in and records his time of arrival. To do this he grasps the knob 29, moves the same to the slot 13, representing his individual space or position, and moves the knob downward into its lowermost posi-

tion, as indicated in Fig. 4. In doing this he compresses the springs 25. This leaves the entire recording-frame free to drop downward by gravity. The frame, therefore, moves downward until the foot 24 thereof engages the uppermost pin 75, as indicated in Fig. 4. The employee next forces the knob directly forward or toward the plate 1, thus causing the frame to rock upon the shaft 15 and force the type-wheels into engagement with the ribbon 67, and thereby impress the card 73 and imprint thereon the ordinals representing the time. The uppermost pin 75 remains in the position indicated in Fig. 4. The employee then releases the knob, which rises into the position indicated in Fig. 3. Each time the knob 29 is released the imprint element is returned to its position of rest or initial position through the action of the springs 25 and associated parts. Any other employee may record his time in the manner just described, but, of course, he uses the slot having his own number and not the slot 13. When employee number 13 again records his time he moves the knob 29, as above described, and always to the same point. The recording-frame drops downward, but not to the same extent, that is to say, the frame moves one step farther and the foot 24 engages the next pin 75. When the knob 29 is pushed in again, the foot 24 causes the second pin to be forced backward. Thus successive and uniform movements of the knob 29 and arm 27 by the same workman in the act of recording effects variable movement of the imprint element from its position of rest, the extent thereof being determined by the part 75. The gradual lowering of the recording-frame resulting from successive operations of the machine by an employee causes time-records to be printed in vertical rows upon the cards; that is to say, employee number 13 first prints his time of arrival upon the top of the card, the next day or the next period of his registration he prints the ordinals representing the time of his arrival in the space next to the top upon the card, the third time he uses the space third from the top, and so on. Each employee's time is, therefore, indicated in a vertical row. If one, or more employees fail to register, this does not disturb the time-records of those who do register. It will be noted that the knob 29 can not be pressed inward until the head 30 is free to pass below the blocking-bar 31. Because of this the frame 23 will always drop a sufficient distance to engage the proper pin 75. In other words, the vertical distance traversed by the knob is sufficient to allow the full movement of the recording-frame, so that said frame may engage the lowermost pin of a row, and the only thing that prevents the frame from going to its lowermost position each time is the

fact that its path is obstructed by one or more pins. A record-receiving element, such as 73, having thereon a plurality of side-by-side record-receiving spaces, each individual to a workman, is preferably used in connection with my machine. As is apparent from the foregoing description, the spacing of the entries of each workman is effected independently of the spacing of the entries for any other workman, and the entries of each workman are separated from one another by substantially equidistant spaces. It will be seen that this card contains record spaces capable of presenting in tabulated form the total time of all the employees considered individually and collectively. 80

What I claim is:

1. In a workman's time recorder, the combination with a time-printing mechanism comprising an impression making element, and an impression receiving element of manually operated means for bringing one element toward the other to make an impression on the receiving element, and mechanism brought into action by said means whereby one element is shifted after the first registration and succeeding impressions representing the arrival and departure of the same workman are recorded in different places on the receiving element. 95

2. In a workman's time recorder, the combination with a time marking mechanism operable to record the times of arrival and departure of the same workman at different printing points, of a manual and connections for shifting the marking mechanism after the first registration by the same workman and for moving the marking mechanism to its printing position by the same operation of the manual by the same workman. 100

3. In a workman's time recorder, a time printing wheel and a shifting mechanism therefor, in combination with a workman's manual connected to actuate both said wheel and said mechanism in the same operation. 110

4. In a workman's time recorder, a time printing device and operating means therefor, in combination with mechanism brought into action by said means at each successive printing operation by the same workman after the first registration to shift the printing device and thereby cause successive impressions by the same workman to be made at different points. 115

5. In a workman's time recorder, the combination of a workman's manual and a time printing wheel brought into printing action and also shifted by said manual by each successive printing operation by the same workman. 125

6. In a workman's time recorder, a printing mechanism, and operating means therefor, in combination with means brought into action by said operating means at each suc- 130

- cessive printing operation by the same workman after the first registration for shifting the printing mechanism different distances.
- 5 7. In a workman's time recorder, a time marking device and operating means therefore, in combination with means brought into action by said operating means just before each successive printing operation to shift the marking device to a different printing position. 70
8. In a workman's time recorder, the combination with time printing elements, of separate means brought into action by the first-named means at each successive operation after the first registration by the same workman to shift one of the elements whereby successive impressions for the same workman are made side by side upon the record sheet. 80
9. In a workman's time recorder, a frame, a platen supported in printing position by the frame, a time-stamp also supported by the frame and operable toward and from and transversely of the platen, and an operating manual operatively connected to effect such movements in a single operation. 85
10. In a time recorder, the combination with a printing element and its operating means including a manual, of means brought into action by said manual to shift said element to a different position at each printing operation by the same workman after the first registration. 90
11. In a time recorder, the combination with a time printing element and its operating means, including a manual, of means brought into action by said manual to shift said element to a different position at each printing operation by the same workman after the first registration, and further means for returning the printing element to its starting position after each printing operation. 95
12. In a time recorder, an impression making element and an impression receiving element, a manual connected to move one element to make an impression on the receiving element, means brought into action by the manual to shift one of the elements at each printing operation by the same workman after the first registration and means to stop the shifted element in different positions after the first printing operation. 100
13. In a time recorder, a time printing device and its operating mechanism, means brought into action by the operating mechanism to shift said device, and additional means also brought into action by said operating mechanism to limit the shifting movement of the printing device to different positions at each printing operation by the same workman after the first registration. 105
14. In a time recorder, a printing device and its operating mechanism, connections between said mechanism and printing device for shifting the latter, and movable means also brought into action by said mechanism for engaging one of said connections and limiting the shifting movement of the printing device to different positions at each printing operation by the same workman after the first registration. 110
15. In a workman's time recorder a printing element, and an impression receiving element, in combination with manually operated means for shifting one of the elements different distances at each successive printing operation by the same workman after the first registration. 115
16. In a workman's time recorder, a time printing device, a manual and connections for shifting the printing device, in combination with a plunger actuated by the shifting mechanism and movable members actuated by the plunger one member space at a time and limiting the shifting movement of the printing device. 120
17. In a workman's time recorder, an impression receiving element and an impression making element, a manual and a connection for bringing said elements together for making an impression, and means brought into action by the manual after the first impression is made by the same workman for shifting one of said elements and making a second impression in a different place upon the receiving element at the end of the shift, and means for automatically returning the shifting element to its starting positions after the last impression has been made. 125
18. An employee's time recorder, embodying a blank-carrier and a recording frame operatively connected and one of which is movable relatively to the other in a plurality of different paths across the face of the other and one of which is movable toward the other to form an impression, and clock-operated time-recording means coöperative with said carrier and frame and embodying type-wheels. 130
19. An employee's time recorder, embodying a blank-carrier and a recording frame operatively connected and one of which is movable across the face of the other in two different paths perpendicular to each other and one of which is movable toward the other to form an impression, and clock-operated time-recording means coöperative with said carrier and frame and embodying type-wheels. 135
20. An employee's time recorder, embodying a blank-carrier and a recording frame operatively connected and one of which is movable relatively to the other in a plurality of different paths across the face of the other and one of which is oscillatory toward the other to form an impression, and clock- 140

operated time-recording means coöperative with said carrier and frame and embodying type-wheels.

21. An employee's time recorder, embodying a blank-carrier and a recording frame operatively connected and one of which is movable relatively to the other in a plurality of different paths across the face of the other, manually-operated means for effecting said movement, and clock-operated time-recording means coöperative with said carrier and frame and embodying type-wheels.

22. An employee's time recorder, embodying a blank-carrier and a recording frame operatively connected and one of which is movable relatively to the other in a plurality of different paths across the face of the other, a manually-operated device for effecting both of said movements, and clock-operated time-recording means coöperative with said carrier and frame and embodying type-wheels.

23. An employee's time recorder, embodying a blank-carrier and a recording frame operatively connected and one of which is movable relatively to the other in a plurality of different paths across the face of the other and is also movable toward the other to form an impression, a manually-operated device for effecting all of said movements, and clock-operated time-recording means coöperative with said carrier and frame and embodying type-wheels.

24. An employee's time recorder, embodying a blank-carrier, a recording frame operatively connected with and reciprocatory in two different paths across the face of the blank-carrier to form an impression, a handle secured to said frame for effecting all of said movements of the frame, and clock-operated time-recording means coöperative with said carrier and frame and embodying type-wheels.

25. An employee's time recorder, embodying a blank-carrier, a two-part recording frame operatively connected therewith and the two parts of which are movable in unison in one direction across the face of said blank-carrier and one part of which is movable relatively to the other in another direction across the face of said blank-carrier, and clock-operated time-recording means coöperative with said carrier and frame and embodying type-wheels.

26. An employee's time recorder, embodying a blank-carrier, a two-part recording frame operatively connected therewith and the two parts of which are movable in unison in one direction across the face of said blank-carrier and one part of which is movable relatively to the other in another direction across the face of said blank-carrier and one part of which is also movable toward the blank-carrier to form an impression, and

clock-operated time-recording means coöperative with said carrier and frame and embodying type-wheels.

27. An employee's time recorder, embodying a blank-carrier, a two-part recording frame operatively connected therewith and the two parts of which are movable in unison in one direction across the face of said blank-carrier and are also movable in unison toward the blank-carrier to form an impression and one part of which is movable relatively to the other in another direction across the face of said blank-carrier, and clock-operated time-recording means coöperative with said carrier and frame and embodying type-wheels.

28. An employee's time recorder, embodying a blank-carrier and a recording frame operatively connected and one of which is movable horizontally across the face of the other and is also gravitational across the face of the other, and clock-operated time-recording means coöperative with said carrier and frame and embodying type-wheels.

29. An employee's time recorder, embodying a blank-carrier, a two-part recording frame operatively connected therewith and one part of which is oscillatory toward and from the blank-carrier and is also movable lengthwise of its axis of oscillation across the face of said blank-carrier and the other part of which is oscillatory with the first to form an impression and is also movable relatively to the first in another direction across the face of said blank-carrier, and clock-operated time-recording means coöperative with said carrier and frame and embodying type-wheels.

30. In an employee's time recorder, the combination of a receptacle for holding cards, a frame operatively connected therewith and movable relatively to said receptacle in a plurality of general directions crossing the faces of said cards, and time-controlled printing mechanism mounted upon said frame and embodying type-wheels and free to print intelligible characters upon said cards and in rows crossing each other.

31. The combination, in an organized time recorder structure such as described, of a casing, a blank carrier and a recording frame operatively connected to each other within said casing, one of said elements within the casing being movable relatively to the other in a plurality of different paths across the face of the other, and also movable toward the other to make an impression, and time controlled recording means carried by the movable element.

32. In an employee's time recorder, the combination of a casing, a relatively fixed blank carrier within the casing, a recording frame within the casing movable relatively to the blank carrier in a plurality of differ-

ent paths across the face of the latter and likewise movable toward said carrier, and a clock-operated time recording means carried by said frame and embodying type 5 wheels to contact with the blank when the last named movement is effected.

33. An employee's time recorder, comprising a casing, means for holding cards and free frame mounted within said casing and free 10 to move relatively to said cards in two general directions crossing the faces thereof, revolute printing wheels mounted upon said frame and provided with ordinals, clock-operated means for automatically actuating 15 said wheels step by step, an inking device for said wheels, and mechanism controllable at will for bodily actuating said frame in two independent directions crossing the faces of said cards.

34. An employee's time recorder, embodying a movable record-locating element for determining the position in which a record is to be made on a record medium by an individual employee, and means controlled by 20 separate recording operations of the time-recorder by an employee for positively stopping said movable element in different record-locating positions corresponding to different operations of the time-recorder by 25 said employee.

35. An employee's time recorder, embodying a movable record-locating element for determining the position in which a record is to be made on a record medium by an individual employee, and means controlled by 30 successive operations of the time-recorder by an employee for positively stopping said movable element in successive record-locating 35 positions corresponding to successive operations of the time-recorder by said employee.

36. An employee's time-recorder, embodying a movable record-locating element for determining the position in which a record 40 is to be made on a record medium by an individual employee, stops for positively stopping said movable element in different recording 45 positions corresponding to different operations of the time-recorder by said employee, and means controlled by separate 50 operations of said time-recorder for rendering said stops separately effective.

37. An employee's time recorder, embodying a movable record-locating element for 55 determining the position in which a record is to be made on a record medium by an individual employee, stops for positively stopping said movable element in successive recording 60 positions corresponding to successive operations of the time-recorder by said employee, and means controlled by successive 65 operations of said time-recorder for rendering said stops successively effective.

38. An employee's time recorder, embodying record-locating means movable in dif-

ferent paths for determining the positions in which records are to be made on a record medium by different employees, and means for positively stopping said record-locating means in different record-locating positions 70 in different paths corresponding to different operations of the time-recorder by different employees.

39. An employee's time recorder, embodying record-locating means movable in different paths for determining the positions in which records are to be made on a record medium by different employees, and means for positively stopping said record-locating means in successive record-locating 75 positions in each of a plurality of paths corresponding to successive operations of the time-recorder by each of a plurality of employees.

40. An employee's time recorder, embodying a blank-carrier and recording means one of which is movable different distances across the face of the other, and means controlled by separate recording operations of the time-recorder by an employee for stopping 80 said movable element in different positions corresponding to such operations.

41. An employee's time recorder, embodying a blank-carrier and recording means operatively connected and one of which is 85 movable different distances in a given path across the face of the other, and means controlled by separate recording operations of the time-recorder by an employee for stopping 90 said movable element in different positions in said path, which positions correspond to such operations.

42. An employee's time recorder, embodying a blank-carrier and recording means operatively connected and one of which is 95 movable different distances in a given path across the face of the other, and means controlled by successive operations of the time-recorder by an employee for stopping said 100 movable element in successive positions in said path, which positions correspond to such operations.

43. An employee's time recorder, embodying a blank-carrier and recording means operatively connected and one of which is 105 movable different distances in a given path across the face of the other, and a series of 110 successively-effective stops controlled by successive operations of the time-recorder by an individual employee for locating said movable element in successive recording positions in said path, which positions correspond to successive operations of said time-recorder.

44. An employee's time recorder, embodying a blank-carrier and recording means operatively connected and one of which is 115 movable different distances in a given path across the face of the other, a series of stops 120 adapted to locate said movable element in 125 said path.

successive recording positions in said path, which positions correspond to successive operations of said time-recorder, and means controlled by successive operations of the 5 time-recorder by an individual employee for shifting said stops out of action successively.

45. An employee's time recorder, comprising a card rack, a frame mounted adjacent to the same and free to swing relatively thereto, means controllable at will for bodily translating said frame relatively to the general direction of said card rack, type members connected with said frame, time-controlled mechanism for changing the positions of said type members, a plurality of stops disposed in different relative positions for limiting the motion of translation of said frame relatively to said card rack, and 10 means for bringing said stops into play one at a time so as to cause said printing mechanism to successively engage different portions of said card to be printed.

46. An employee's time recorder, comprising a card rack, a frame mounted adjacent to the same and free to swing relatively thereto, said frame being provided with a foot, means controlled at will for causing said frame to approach and recede 15 from said card rack and also for bodily translating said frame relatively to the general position of said card rack, type members connected with said frame, time-controlled mechanism for changing the positions of said type members, means for inking said type members, a rigid web mounted adjacent to said card rack and provided with movable pins disposed in different positions relatively to said card rack and normally obstructing the path of said foot, the arrangement being such that said pins may be successively displaced by successive movements of said foot as said 20 frame is moved toward and from said card rack, and means for simultaneously restoring all of said pins to a predetermined normal condition.

47. An employee's time recorder, comprising a card rack, a frame mounted adjacent to the same and free to swing relatively thereto, said frame being provided with a foot, means controllable at will for causing said frame to approach and recede 25 from said card rack and also for bodily translating said frame relatively to the general position of said card rack, type members connected with said frame, time-controlled mechanism for changing the positions of said type members, means for inking said type members, mechanism for automatically stopping said frame in different successive positions relatively to said card rack, and a manually operated device for restoring said stop mechanism to a predetermined normal position.

48. An employee's time recorder, comprising a card rack, a frame mounted adjacent to the same and free to swing rel-

atively thereto, said frame being provided with a foot, means controllable at will for causing said frame to approach and recede from said card rack and also for bodily translating said frame relatively to the 70 general position of said card rack, type members connected with said frame, time-controlled mechanism for changing the positions of said type members, means for inking said type members, and stop mechanism for automatically stopping said frame in different successive positions relatively to said card rack for the purpose of printing successive ordinals upon different portions of a card.

49. An employee's time recorder, comprising a card rack, a frame mounted adjacent to the same and free to swing relatively thereto, said frame being provided with a foot, means controllable at will for causing said frame to approach and recede 75 from said card rack and also for bodily translating said frame relatively to the general position of said card rack, type members connected with said frame, time-controlled mechanism for changing the relative positions of said type members, means for inking said type members, a rigid web mounted adjacent to said card rack and provided with movable pins disposed in different positions relatively to said card rack, said pins normally obstructing the path of said foot, the arrangement being such that said pins may be successively displaced by successive movements of said foot as said 80 frame is moved toward and from said card rack, and means for simultaneously restoring all of said pins to a predetermined normal condition.

50. An employee's time recorder, comprising a card rack, a frame mounted adjacent to the same and free to swing relatively thereto, said frame being provided with a foot, means controllable at will for causing said frame to approach and recede 85 from said card rack, and also for bodily translating said frame relatively to the general position of said card rack, type members connected with said frame, time-controlled mechanism for changing the relative positions of said type members, means for inking said type members, a rigid web mounted adjacent to said card rack and provided with movable pins disposed in different positions relatively to said card rack 90 100 said pins normally obstructing the path of said foot, the arrangement being such that said pins may be successively displaced by successive movements of said foot as said frame is moved toward and from said card rack, and means for restoring said pins to a predetermined normal condition.

51. An employee's time recorder, embody-

ing a blank-carrier and recording means one of which has different parallel paths of movement across the face of the other and is movable different distances to such paths, 5 and means controlled by the recording operations for stopping said movable element in different positions in each of said paths.

52. An employee's time recorder, embodying a blank-carrier and recording means one of which is movable different distances in parallel paths across the face of the other, and means controlled by the recording operations for stopping said movable element in successive positions in each of said 10 paths which positions correspond to successive operations of said time-recorder.

53. An employee's time recorder, embodying a blank carrier and recording means one of which is movable different distances in parallel paths across the face of the other, and a plurality of series of stops, one series for each of said paths, each series consisting of a plurality of successively-effective stops for locating said movable element in successive positions in the path corresponding to such series, said positions corresponding to successive operations of said time-recorder. 20 25

54. An employee's time recorder, embodying a blank-carrier and recording means one of which is movable different distances in parallel paths across the face of the other, a plurality of series of stops one series for each of said paths, each series consisting of 30 35 a plurality of stops adapted to locate said movable element in successive positions in the path corresponding to such series, said positions corresponding to successive operations of said time-recorder, and means for shifting the stops of each series out of action successively.

55. An employee's time recorder, embodying a blank-carrier and recording means one of which is movable different distances in parallel paths across the face of the other, a plurality of series of stops one series for each of said paths, each series consisting of a plurality of stops adapted to locate said movable element in successive positions 40 45 50 in the path corresponding to such series, said positions corresponding to successive operations of said time-recorder, and means for shifting the stops of each series out of action successively one stop on each operation of said time-recorder.

56. An employee's time recorder, comprising a casing, means for holding cards, a frame mounted within said casing and movable in two general directions crossing the 55 faces of said cards, printing mechanism mounted within said casing and free to place ordinals upon said cards, means controllable at will for actuating said frame in two independent directions crossing the faces of said cards, and a plurality of movable stops

arranged in a series and free to successively limit the movements of said frame in one of said independent directions.

57. In an employee's time recorder, the combination of a receptacle for holding cards, a frame movable relatively to said receptacle in a plurality of general directions crossing the faces thereof, printing mechanism mounted upon said frame and free to print intelligible characters upon said cards and in rows crossing each other, and movable stops for successively limiting the movements of said frame in one of said general directions. 70 75

58. An employee's time recorder, comprising a casing, means for holding cards, a frame mounted within said casing and free to move relatively to said cards in two general directions crossing the faces of said cards, printing mechanism mounted upon said frame for placing time ordinals upon said cards, and a plurality of movable stops arranged in a series and free to successively limit the movements of said frame in one of said general directions, the arrangement being such that said ordinals may be printed in a plurality of rows each row representing the time of an individual. 80 85 90

59. An employee's time recorder, comprising a card receptacle, a frame mounted adjacent thereto and free to move relatively to said card receptacle in two directions crossing each other, printing mechanism mounted upon said frame, a time-controlled device connected with said printing mechanism, movable pins for successively limiting movements of different degree in said frame in one direction thereof, and means for successively removing said pins for the purpose of allowing said printing mechanism to print upon different portions of a card successively. 95 100 105

60. An employee's time recorder, embodying a blank-carrier and recording means one of which is movable across the face of the other different feed distances representing different periods of a day and one of which is movable to effect an impression, said recording means including type-wheels, means for effecting said feed movements and impression movement, and a rectilinear blocking bar for preventing an impression movement until the completion of said first mentioned feed movement. 110 115

61. An employee's time recorder, embodying a blank-carrier and recording means one of which is movable different feed distances across the face of the other and one of which is movable to effect an impression, means for stopping in different positions the element having the feed movements, controlling means having feed-controlling and impression-controlling movements governing said feed-movements and impression movement, and a rectilinear blocking bar for prevent- 120 125 130

ing an impression movement until completion of the feed-controlling movement of said controlling means and also the feed movement.

5 62. An employee's time recorder embodying a blank-carrier, recording means movable different distances across the face of said blank-carrier, controlling means governing said feed-movements and having a
10 feed-controlling movement corresponding to the maximum feed movement of said recording means, and a rectilinear blocking bar for preventing impression until the completion of said feed-controlling movement
15 and also the feed movement.

63. An employee's time recorder, embodying a blank-carrier and recording means one of which is movable across the face of the other in two directions crossing each other, 20 means for effecting both of said movements, and blocking means operative in all positions of said movable member in one of said crossing directions for preventing impression until a predetermined point in the 25 movement of said member in the other of said crossing directions.

64. An employee's time recorder, embodying a blank-carrier and recording means one of which is movable across the face of the 30 other different feed distances in each of two directions across each other, means for stopping said movable member in different positions in one of said directions, controlling means having feed-controlling and impression-controlling movements governing said 35 last-mentioned feed-movement and also governing the impression movement, and blocking means for preventing the impression movement until the completion of the feed- 40 controlling movement of said controlling means.

65. An employee's time recorder, embodying a blank-carrier and recording means one of which is movable across the face of 45 the other different feed-distances in each of two directions across each other, means for stopping said movable member in different positions in one of said directions, controlling means having feed-controlling and impression-controlling movements governing said 50 last-mentioned feed-movement and also governing the impression movement, and a blocking-bar coöperative with said controlling means in all positions of the latter for preventing the impression movement until 55 the completion of said feed-controlling movement of the controlling means.

66. An employee's time recorder, embodying impression-producing means including 60 type-wheels, a controlling device having two movements transverse to each other one of which governs impression, and relatively fixed blocking means over which said controlling device must pass transversely prior 65 to an impression movement.

67. An employee's time recorder, embodying impression-producing means including type-wheels, a controlling device having two movements transverse to each other one of which governs impression, and a blocking 70 bar over which said controlling device must be manually passed in a transverse direction prior to the impression movement.

68. An employee's time recorder, embodying impression-producing means, a controlling device having three movements two of which are in paths transverse to each other and the third of which is in a path transverse to the other two and governs impression, and blocking means coöperative with 80 said controlling device in all of the positions of said controlling device in one of said first two paths for preventing the impression-controlling movement of said controlling device until the completion of the movement 85 of said device in the second of said paths.

69. An employee's time recorder, embodying impression-producing means, a controlling device having three movements two of which are in paths transverse to each other 90 and the third of which is in a path transverse to the other two and governs impression, and a blocking-bar coöperative with said controlling device in all of the positions of said controlling device in one of said first 95 two paths for preventing the impression-controlling movement of said controlling device until the completion of the movement of said device in the second of said paths crosswise of said blocking-bar. 100

70. An employee's time recorder, comprising a casing, means for holding cards, a frame mounted within said casing and free to move relatively to said cards in two general directions crossing the faces thereof, 105 revoluble printing wheels mounted upon said frame and provided with ordinals, electric mechanism for actuating said wheels step by step, an inking device for said wheels, a magnet for intermittently energizing said electric mechanism, and means controllable at will for bodily actuating said frame in such two general directions crossing each other. 110

71. An employee's time recorder, embodying the following two main elements, viz.—a blank-carrier and electrically operated time-recording means associated therewith and having type-wheels—one of which main elements is movable in a plurality of different paths across the face of the other and one of which is also movable toward the other to form an impression. 115

72. An employee's time recorder, embodying the following two main elements, viz.—a blank-carrier and electrically-operated time-recording means associated therewith and having type-wheels—one of which main elements is movable in a plurality of different paths across the face of the other and is 120

also movable toward the other to form an impression.

73. An employee's time recorder, embodying the following two main elements, viz.—
5 a blank-carrier and time-recording means associated therewith and having type-wheels the rotation of which is controlled electrically by means outside said time-recorder and forming no part thereof—one of which main

10 elements is movable in a path across the face of the other and one of which is movable in another path across the face of the other and one of which is also movable toward the other to form an impression.

15 74. An employee's time recorder, embodying the following two main elements, viz.—
a blank-carrier and time-recording means associated therewith and having type-wheels the rotation of which is controlled electrically by means outside said time-recorder and forming no part thereof—one of which main elements is movable in a plurality of different paths across the face of the other and one of which is also movable toward
20 25 the other to form an impression.

75. An employee's time recorder, embodying the following two main elements, viz.—
a blank-carrier and clock-operated time-recording means associated therewith and having type-wheels—one of which main elements is movable in a plurality of different paths across the face of the other and is also movable toward the other to form an impression.

35 76. In combination, a printing mechanism, a card-holder therefor, said printing mechanism and said card holder being relatively movable in perpendicular directions and means for regulating the position of one of
40 said co-operative elements with reference to the other such that impressions on a card carried by said card-holder may be spaced by such means in successive longitudinal and transverse columns.

45 77. In an employee's time recorder, a movable record locating element common to a plurality of workmen, and means individual to each workman and controlled by the separate recording operations of the workmen to which said means is appropriated, for positively stopping said movable element in different printing positions corresponding to the different operations of the time-recorder by such workman.

55 78. In a workman's time-recorder, and in combination, an imprint element and a support for an imprint-receiving element, said parts having relative movement for providing substantially equidistant spaces between
60 successive imprints, or entries, and independent means individual to the separate workmen for controlling the spacing movement.

79. In a workman's time-recorder, and in
65 combination, an imprint element and a sup-

port for an imprint-receiving element, said parts having relative movement for providing substantially equidistant spaces between successive imprints, or entries, and independent means individual to the separate workmen for controlling the spacing movement, said means including displaceable parts and means for restoring the displaced parts.

70 80. In a time-recorder, and in combination, an imprint element and a support for an imprint-receiving element, said elements having relative movement variable distances from an initial position, and means individual to the workman for controlling the extent of said movement, said means including a series of displaceable parts individual to the workman.

75 81. In a time-recorder for a plurality of workmen, an imprint-making element, a support for an imprint-receiving element, said imprint-making element and support having relative movement variable distances in parallel paths, and means for controlling such movements including a plurality of parts individual to each path.

85 82. In a time-recorder for a plurality of workmen, an imprint-making element, a support for an imprint-receiving element, said imprint-making element and support having relative movement variable distances in parallel paths, and means for controlling such movements including a plurality of parts individual to each path, said parts being movable into ineffective positions one at a time.

83. In a time-recorder for a plurality of workmen, an imprint-making element, a support for an imprint-receiving element, said imprint-making element and support having relative movement variable distances in parallel paths, means for controlling such movements including a plurality of parts individual to each path, said parts being movable into inoperative positions one at a time, and means for restoring the parts to operative positions.

105 84. In a time-recorder for a plurality of workmen, an imprint-making element, a support for an imprint-receiving element having record-spaces individual to the workmen, said elements having relative movement for effecting spacing between the entries made in each record space, and means for controlling such movement, including a series of displaceable parts associated with each record space, and means for restoring the displaced parts to their initial positions.

115 85. In a time-recorder for a plurality of workmen, an imprint-making element, a support for an imprint-receiving element having record-spaces individual to the workmen, said elements having relative movement for effecting spacing between the

130

entries in each record space, and means for controlling such movement including a series of displaceable parts and a coöperating member designed to be arrested by and to displace said parts, and a single part coöperating in one movement with all of the displaced members for restoring the same to initial positions.

86. In a time-recorder for a plurality of workmen, an imprint - making element, a support for an imprint-receiving element having spaces individual to the workman, a hand - operated part operatively connected for shifting one of the elements for bringing the imprint - element and a selected space into alinement, and for moving the parts relatively in a second direction for bringing the imprint element and a predetermined portion of the selected space into registration, said parts also having relative movement in a third direction for printing, and mechanical means for controlling the extent of said second movement, said means having parts which are shifted in one of said movements of the parts.

87. In a workman's time - recorder, a printing couple comprising a support for a record-receiving element having a space for receiving a plurality of spaced apart imprints and an imprint-making element, the members of the couple having relative movement for bringing the same into proper printing relation, and means for determining such relation, including a group of displaceable parts automatically displaceable by the manual movement of one of said members of the printing couple.

88. In a workmen's time-recorder for a plurality of workmen, a support for a record-receiving element having record spaces individual to the workmen for receiving a plurality of spaced apart imprints, an imprint-making element, and means for determining the positions of the imprints in each record space, said means including a separate group of displaceable parts individual to each workman, and means for displacing the parts of each group in succession, the order in which said parts are displaced being beyond the control of the workman.

89. In a workmen's time-recorder for a plurality of workmen, an imprint-making element, a support for an imprint-receiving element having record spaces individual to the workmen for receiving a plurality of entries individual to him, and means for determining the positions of the imprints in each space, said means including a plurality of displaceable parts individual to each space, each of such parts corresponding to a predetermined position of an imprint, and means for displacing said parts.

90. In a workmen's time-recorder, an imprint-making element, a support for an im-

print-receiving element designed to receive a plurality of entries spaced apart, and means for determining the spacing including a plurality of automatically shiftable non-clock-controlled displaceable parts, each part corresponding to an entry-receiving space, and means for displacing the parts through the operation of the recorder by a workman.

91. In a time-recorder for a plurality of men, an imprint element, a support for an imprint-receiving element having spaces individual to the men, means tending to hold said elements in a position of rest, or initial position, a handle movable into independent positions complemental to said spaces for bringing any space and imprint element into alinement, said handle having an additional movement when in any one of said individual positions, said imprint element and support having relative movement away from said position of rest and in a direction lengthwise of the alined space when the handle is given the additional movement, and means for determining the extent of said lengthwise movement including a plurality of parts individual to each individual position of the handle and operating for controlling the movement when the handle occupies a position complemental thereto.

92. In a workmen's time-recorder for imprinting on a receiving surface a plurality of entries spaced apart, a spacing mechanism comprising a plurality of parts, each part being complemental to an individual entry-receiving point on said surface, and a coöperating member common to all of said parts designed to be arrested by and operating for moving the parts out of operative positions individually.

93. In a workman's time-recorder for imprinting on a receiving surface a plurality of entries spaced apart, and including a printing couple, a spacing mechanism comprising a plurality of displaceable parts, each complemental to an individual entry-receiving point on said surface, and a co-operating element common to all of said displaceable parts and fixed relative to a shiftable member of the printing couple, said member of the printing couple being shiftable in a direction for effecting spacing, and said element in such movement being arrested by the displaceable parts and operating thereon for shifting the parts individually out of arresting position.

94. In a time-recorder, a printing couple comprising members relatively movable for spacing between successive imprints, a plurality of parts each complemental to an individual imprint position, and a device associated with one member of the couple and coacting with said parts for positioning the members of the couple, said device also acting to successively shift the parts out of

effective positions, and means for restoring the displaced parts to effective positions.

95. In a time-recorder, a printing couple comprising elements relatively movable for spacing between successive imprints, a plurality of parts each complementary to an individual imprint position, means for shifting said parts out of effective positions, and a plate movable about an axis for restoring the displaced parts to their initial positions.

96. In a time-recorder, a printing couple comprising elements relatively movable for spacing between successive imprints, a plurality of parts each complementary to an individual imprint position, means for shifting said parts out of effective positions, and a plate movable toward and from the parts for restoring the displaced parts to their initial positions.

97. In a time-recorder, a printing couple comprising elements relatively movable for spacing between successive imprints, a plurality of parts each complementary to an individual imprint position, means for shifting said parts out of effective positions, and means for moving the plate into engagement with the displaced parts for restoring the same to their initial positions.

98. In a time-recorder, a printing couple comprising elements relatively movable for spacing between successive imprints, a plurality of parts each complementary to an individual imprint position, means for shifting said parts out of effective positions, a restoring plate for said parts and means for bringing the plate in a single movement thereof into engagement with a plurality of displaced parts for restoring the same to their initial positions.

99. In a recorder for printing on a single sheet entries of a plurality of men in spaces individual to the men, and with the successive entries of each man separated from one another, an impression making element, and an element carrying an impression receiving surface, the elements having relative movement in one direction for alining any selected space and the impression making element, and having relative movement in a second direction for effecting said spacing between successive entries, a manual operatively connected for effecting said relative movements, and a mechanism for controlling the extent of said second relative movement.

100. In a recorder for printing on a single sheet entries of a plurality of men in spaces individual to the men, and with the successive entries of each man separated from one another, an impression making element, and an element carrying an impression receiving surface, the elements having relative movement in one direction for alining any selected space and the impression making element, and having relative movement in a

second direction for effecting said spacing between successive entries, a manual operatively connected for effecting said relative movements, and a mechanism for controlling the extent of said second relative movement, 70 said mechanism including a plurality of parts individual to each workman.

101. In a recorder for printing on a single sheet entries of a plurality of men in spaces individual to the men, and with the successive entries of each man separated from one another equidistantly, an impression making element, and an element carrying an impression receiving surface, the elements having relative movement in one direction for registering any selected space and the impression making element, and having relative movement in a second direction for effecting said spacing between successive entries, a manual operatively connected for 80 effecting said relative movements, and a mechanism for controlling the extent of said second movement including means individual to each man, and a device common to all of the men coöperating with the individual means.

102. In a recorder, an impression making element, and a second element for holding an impression receiving surface, a manual operatively connected for effecting a relative movement of said elements in one direction, or path, from an initial position, and means for controlling the extent of said movement so that under each successive actuations of said manual by the same workman the range of said relative movement 100 will be increased.

103. In a recorder, an impression making element, and a second element for holding an impression receiving surface, a manual 105 operatively connected for effecting a relative movement of said elements in one direction, or path, from an initial position, and means for controlling the extent of said movement so that under each successive actuations of said manual by the same workman the range of said relative movement 110 will be increased, and means for restoring the said elements to said initial position after each recording operation.

104. In a recorder, an impression making element, and a second element for holding an impression receiving surface, a manual operatively connected for effecting a relative movement of said elements in one direction or path from an initial position, and means for so controlling the extent of said movement that under successive actuations of said manual, by the same workman, the range of said relative movement will be increased, said means including a member movable with one of said elements and a plurality of coöperating parts displaceable by said member.

105. In combination, the printing mecha-

nism, a card-holder therefor, a relatively fixed group of stops controlling the movement of one of said coöperative elements in one direction, by which stops the relation 5 in said direction between the printing mechanism and the card-holder can be determined, means controlling the movement of the same coöperative element in a direction transverse to its said first movement, 10 and means for changing the positions of said stops whereby they are successively brought into position longitudinally of the holder.

106. In combination, the printing mechanism, a card-holder therefor, a relatively fixed group of stops controlling the movement of one of said coöperative elements in one direction and adapted to coöperate separately with said printing mechanism and 15 card holder to determine the relation in said direction between the printing mechanism and a card in said holder and means controlling movement of the same coöperative element in a direction transverse to its said 20 first movement.

107. In combination, the printing mechanism, a card-holder therefor, a relatively fixed group of stops controlling the movement of one of said coöperative elements 30 in one direction and adapted to coöperate separately with said printing mechanism and card-holder to determine the relation in said direction between the printing mechanism and a card in said holder, means controlling movement of the same coöperative element in a direction transverse to its said 35 first movement and means for bringing said stops into action at determined intervals.

108. In combination, the printing mechanism, a card-holder therefor, a relatively fixed group of stops controlling the movement of one of said coöperative elements in one direction and adapted to coöperate separately with said printing mechanism and 40 card-holder to determine the relation in said direction between the printing mechanism and a card in said holder, means controlling movement of the same coöperative element in a direction transverse to its said first 45 movement and means for bringing said stops into action successively.

109. In a device of the class described, in combination with the printing mechanism and the card-holder in operative relation 55 thereto, a plurality of stops spaced longitudinally and transversely and controlling a movement of one of said coöperative elements in one direction, means controlling movement of the same coöperative element 60 in a direction transverse to its said first movement, and means for separately bringing said stops into action to determine the first mentioned relation between the print-

ing mechanism and a card in the card-holder.

110. In a time recorder, printing mechanism, a card-holder, a relatively fixed group of stops controlling the movement of one of said coöperative elements in one direction and located outside the card-holder, 70 means controlling movement of the same coöperative element in a direction transverse to its said first movement and means for separately moving said stops into position to determine the first mentioned relation between the printing mechanism and a card 75 in said holder.

111. In a time recorder, the combination of a time-controlled stamp, a card-holder in operative relation to said stamp, a relatively fixed group of abutments controlling the movement of one of said coöperative elements in one direction and movement between the card-holder and said stamp, said abutments serving to permit the stamp to 80 print at different points on the card, and means controlling movement of the same coöperative element in a direction transverse to its said first movement.

112. In a time recorder, the combination 90 with a time stamp, of a card-holder, a relatively fixed group of stops controlling the movement of one of said coöperative elements in one direction and to successively vary the relation between the time stamp 95 and a card in said card-holder, means controlling movement of the same coöperative element in a direction transverse to its said first movement and means to bring one stop after another into operative position. 100

113. The combination with a time stamp, of an upright card-holder, means to gradually vary the effective depth thereof, said means controlling the movement of one of said coöperative elements in one direction 105 and including a relatively fixed group of members adapted to coöperate one by one with said card-holder, mechanism to render said members operative in succession, and means controlling movement of the same coöperative element in a direction transverse to its said first movement. 110

114. The combination, with a time stamp, of a card-holder adjacent thereto, a series of stops located in parallel planes at right 115 angles to the card-holder and individually movable to determine the printing position, and means to render said stops operative one by one in regular sequence.

— Signed at New York, in the county of 120 New York and State of New York, this 27th day of December, A. D. 1904.

HARRY B. PALMER.
